UNITED STATES PATENT OFFICE.

BENJAMIN D. TRAITEL AND JACOB RAWISZER, OF NEW YORK, N. Y.; SAID RAWISZER ASSIGNOR TO SAID TRAITEL.

JEWELRY.

SPECIFICATION forming part of Letters Patent No. 394,523, dated December 11, 1888.

Application filed May 21, 1888. Serial No. 274,611. (No model.)

To all whom it may concern:

Be it known that we, BENJAMIN D. TRAITEL and JACOB RAWISZER, citizens of the United States, residing at New York, in the county of New York and State of New York, have jointly invented a new and useful Improvement in Jewelry, of which the following is a specification.

Our invention relates to improvements in jewelry, and has special reference to that class of articles employed for personal adornment provided with interchangeable mountings or settings.

Our invention consists in a novel device that will securely lock a stone or mounting within the frame or box of a ring, locket, or analogous article, and from which by a simple movement it can be readily released and another substituted therefor, all as hereinafter fully described; illustrated in the drawings, and specifically pointed out in the claims.

Referring to the accompanying drawings, in which like letters of reference point out similar parts on each figure, Figure 1 is a front and rear perspective view of a closed ring embodying our invention. Fig. 2 is a front view, the stone or setting being removed, showing the sliding plate extended downwardly in position to receive the projecting pins of the mounting. Fig. 3 is a like view showing the sliding plate slid upwardly in position to lock the mounting in place. Fig. 4 is a view of the locking-plate detached from the ring. Fig. 5 is a cross-sectional view on the line xx of Fig. 3, with an enlarged detail view of the interior side flange. Fig. 6 is a modification showing means for holding the mounting in place without employment of orifices on the back lining-plate of the box. Fig. 7 is a rear view of the mounting detached from the box of the ring.

We shall confine the description of our device to employment on a ring, although we do not limit ourselves to such use, the invention being equally adapted for application in lockets, bracelets, ear-rings, and analogous articles of personal adornment.

A represents the mounting, which is provided with one or more notched studs or pins, a , extending rearwardly therefrom.

B is a shallow open box consisting of a back

panel, b , having uprising therefrom sides b' and ends b^2 .

In the drawings we illustrate a quadrangular box, but do not limit ourselves to such form, as said box may be of any shape or configuration to conform with the perimeter of the mounting to be inserted therein. The panel b is preferably supplied with one or more orifices, b^3 , to receive the pins a of the mounting. Inside of said box along one of its sides is a flange, 1, reaching the full length thereof, thus forming an annular groove or channel, 2, for the free passage upward and downward therein of the holding-plate C, one side edge of which in practice is inserted within said channel. At the opposite side and within said box at its upper part is a permanently-attached short open-ended tube, b^4 , the opening of which conforms to an aligning orifice, b^5 , in the upper end, b^2 , of the box B, the opposite end of said box being supplied with a like orifice, b^6 .

C is the holding-plate. It is somewhat shorter in length than the box in which it operates and within which it is adjusted to be slid up and down. The side opposite the one to be inserted within the groove 2 is provided with a vertical pin, c , which extends a short distance above and below said plate, (see Fig. 84,) but which pin is of the exact length of the box B, so that when inclosed therein no portion will extend beyond the frame of said box; but the opposite terminals of said pin will lie snugly within openings b^5 b^6 and flush with the surface of the opposite ends of the box-frame. Said pin is closely connected the full length of the side of the plate, except where cut away therefrom by an upper short slit, c' , for a purpose presently set forth.

The plate C is provided with one or more apertures, each consisting of a circular orifice having extending therefrom and opening therein a straight open arm, said arm and circular orifice composing what are generally known as and are herein denominated "key-hole slots" c^2 c^2 , and its surface is in alignment with the plane of the back lining of the box B when the key-hole slots are employed in combination with orifices b^3 on the panel b .

Our invention broadly consists of the devices as thus described; but they are suscep-

table of certain modifications, which may be employed in connection therewith without departing from the leading scope and purview of said invention, as follows: The orifices b^3 in the panel b may be dispensed with, if desired, in which case the locking-plate must be curved or arched, (see Fig. 6,) thereby leaving a space between the lower surface of said plate and the upper surface of the panel b of sufficient depth to admit therein the notched pins a of the mounting A.

In the drawings we illustrate a small spring, s , which may, if desired, be attached either to the end of the plate or within the box, the function of which spring will be to maintain the plate C always pressed upwardly within the box, but which spring will readily yield when said plate is moved in a contrary direction.

From the foregoing description, in connection with the drawings, the nature and object and the operation of our invention will be readily understood by all persons familiar with the line of art to which our improvement is allied.

Its operation may be briefly explained as follows: The incasement or box B, being without any mounting, has the plate C pushed downwardly into the position illustrated in Fig. 2. This is effected by pressing a wire or ordinary pin upon the upper exposed end of the pin c , which is seated within the orifice b^5 at the upper end of the box-frame. (See indicating arrows.) The result will be that the lower end of the pin c will be ejected through the aperture b^6 upon the lower end of the box-frame, while at the same time the upper end of the pin c will pass downwardly within the short tube b^4 . It will be manifest that the opposite edge of the plate C, being confined within the annular groove 2, will slide therein, and there will be no risk of displacing said plate laterally or otherwise. The circular member of each key-hole slot will be thus brought into juxtaposition with the underlying orifices b^3 of the panel b , and the respective openings will coincide. The mounting is now inserted in place, the pins a thereof taking within the respective united openings of the sliding plate and panel, which have been brought into alignment, as before set forth. Pressure is now applied (in direction of arrow w) to the lower end of the pin c , which is projecting downwardly through the under edge of the frame. The effect will be that the plate C is pushed upwardly into the position shown in Fig. 3, and the device is securely locked in place.

The same operation is followed when an arched plate, as shown in Fig. 6, is employed, and wherein the orifices upon the panel b are dispensed with, for it will be readily understood that in that case the narrowed portion of the key-hole slots will securely grasp the notched pins a when caused to embrace said pins by sliding the plate C into proper position.

If a more firm grip be required, it can be secured by means of a spring, s . Such a spring, however, is by no means essential in practicing our invention, for the plate cannot move in its ways unless the pin c is subjected to direct and positive pressure. There is no risk of any such pressure being accidentally imparted thereto, for it will be observed that the ends of said pin are flush with the respective planes of the upper and lower ends of the box-frame, that the diametrical size of the pin c is quite small, and that the opposite terminals of said pin entirely fill up the orifices into which they fall. Thus a blow or pressure upon either edge of the box-frame will not move the sliding plate unless intentionally exerted directly upon the flat end of the pin c , and such pressure not extending beyond the diameter of a cross-section of said pin.

Having thus explained our invention and its operation, what we claim is—

1. A finger-ring or analogous article of personal adornment having within a box-frame a reciprocally-sliding plate pierced with one or more key-hole slots, as herein shown and described, in combination with an interchangeable mounting provided with rearwardly-extending notched studs adapted to mesh with the slots of said sliding plate, substantially as described.

2. An article of jewelry supplied with an open-box incasement for reception of an interchangeable mounting, said box having a rear panel, b , provided with one or more orifices, b^3 , side frames, b' , and upper and lower end frames, b^2 , provided, respectively, with apertures b^5 b^6 , said box supplied upon one of its sides interiorly with a flange, 1, forming an annular groove, 2, and at its opposite side interiorly, near its upper end, with a permanently-attached short open-ended tube, b^4 , in combination with a sliding plate, C, having lengthwise of one of its sides a pin, c , extending a short distance above and below the upper and lower edges of said plate, the terminals of said pin adapted to lie, respectively, within the orifices b^5 b^6 when the device is closed and movable upward and downward within the box B, whereby when said plate is pressed downwardly within said box the lower end of the pin c will pass outwardly through the orifice b^6 , and the upper end thereof be guided within the tube b^4 , as and for the purpose intended, substantially as described.

3. An article of jewelry provided with a receptacle for insertion therein of an interchangeable mounting, A, having one or more rearwardly-extending notched pins, a , in combination with an arched plate, C, provided with key-hole slots c^2 , adapted to intermesh with said notched pins and from which they will be released by the downward motion of said plate C, as and for the purpose intended, substantially as described.

4. The combination of the sliding plate C, constructed as described, and its incasement

B, with a pressure-spring, *s*, substantially as described.

5. An article of jewelry consisting of the following elements: an open incasement, *B*, having uprising from a back panel, *b*, opposite sides *b'*, upper and lower uprising ends *b²* *b³*, said ends having aligning apertures *b⁵* *b⁶*, a short open-ended tube, *b⁴*, permanently attached to and within the upper part of one 10 side of the incasement *B*, directly below the aperture *b⁵* and opening therein, an annular groove, *2*, at the opposite side within said incasement and extending the full length thereof, a sliding plate, *C*, provided with key-hole

slots *c²*, side pin, *c*, extending beyond the upper and lower edges of said plate, said pin separated a portion of its length from said plate by a short slit, *c'*, and a removable mounting, *A*, having rearwardly-extending notched pins *a*, all constructed and arranged as illustrated and described, as and for the purpose intended, substantially as set forth. 15 20
